EDWARD JOSEPH WILSON, JR., OF WHITE PLAINS, NEW YORK.

DIRECTION-INDICATING MECHANISM.

Application filed March 10, 1923. Serial No. 624,181.

To all whom it may concern:

Be it known that I, EDWARD JOSEPH WILSON, Jr., a citizen of the United States, and a resident of White Plains, in the county of 5 Westchester and State of New York, have invented a new and Improved Direction-Indicating Mechanism, of which the following is a full, clear, and exact description.

This invention relates to improvements in 10 switching devices for operating signals and has particular reference to a mechanism for controlling the operation of direction indicating signals for vehicles.

An object of the invention is to provide an 15 improved device which is controlled by movements of the steering post of a vehicle to operate a signal, or signals, to indicate the direction in which the vehicle is turning.

A further object is to so construct the 20 switching device that the wear on certain parts, incident to repeated use, may be readily and quickly taken up.

The above and other objects will appear 25 more clearly from the following detail description, when taken in connection with the accompanying drawing, which illustrates a preferred embodiment of the inventive idea.

In the drawing—

Figure 1 is a longitudinal section through 30 the switching device illustrating diagrammatically the operating circuits and signals controlled thereby; and

Figure 2 is a side elevation of the switching 35 device showing the manner of mounting the same in association with the steering post of a vehicle.

Referring more particularly to the drawing, the numeral 5 indicates the steering post of a vehicle which, in the usual manner, 40 extends through the wall 6 separating the engine from the driver's compartment.

The switching device, which comprises the essential features of the invention, includes a circular casing 7 made of any desirable material and having a radially extending opening 8 therein for receiving the steering post 5, the length of said opening being such that when the steering post is at the inner end thereof, the casing will be disposed concentrically with respect to said post. The casing 7 is supported in its operative position in association with the steering post by means of an angular bracket 9, the ends of which are secured to the wall 6 and the top of the casing 7 in any preferred manner.

Secured within the casing 7 between the top and bottom thereof are the oppositely disposed insulating members 10 of arcuate formation to conform to the contour of the casing, the adjacent ends of said members being spaced, as clearly shown in Figure 1. Associated with each of the members 10 is a stationary contact segment 11, also of arcuate formation, held in operative position by means of a terminal post 12, the inner end of which is secured to the adjacent end portion of the segment 11 to support the same in proper position within the casing.

A collar 13 is secured to the steering post 5 in any desired manner and carries a movable contact 14 in such manner that said contact may be engaged with the segments 11 when the steering post 5 is turned in either direction. When the post is in its normal position the contact 14 is positioned in the space between adjacent ends of the segments 11 and this space is of sufficient width to permit of the usual play in the steering post without causing the contact 14 to engage either of the segments. However, when the steering post is turned sufficiently to change the direction of travel of the vehicle, the contact 14 will engage 75 one of the segments 11 and thus close a circuit for operating a signal, or signals, which indicates the direction in which the vehicle is turning.

In order to compensate for the wear occasioned by repeated engagement of the contact 14 with the segments 11, means are provided for radially adjusting the segments 11 so that the contact 14 will always engage 80 said segments when the steering post is rotated. This means preferably includes a segment adjusting plate 15 normally positioned within a recess 16 formed in the inner surface of each insulating member 10. Said plate conforms to the contour of the member 10 and the associated segment 11 and is interposed between the same so that an inward adjustment of the plate will also force the engaged segment 11 in the same direction. To adjust either of the segments inwardly 85 the nut of the terminal post 12 which carries such segment is first loosened and then either or both of the screws or other suitable adjusting devices 17 are turned to exert an inward pressure upon the plate 15. In this manner the segment 11 may be adjusted 90 until its entire contacting surface will be engaged by the contact 14 as the steering post 100 105 110

5 is rotated. The nut of the terminal post may again be tightened to securely retain the segment 11 in its adjusted position.

The signals employed in connection with the switching device are preferably, though not necessarily, visible signals, as shown in Figure 1, and one set 18 may be mounted upon the rear of the vehicle and a second set 19 either on the front of the vehicle, or 10 on the instrument board. In the latter case, the set 19 would be employed merely for the purpose of indicating to the driver that the operating circuits for the set 18 were in proper working order. The lamps of the 15 two sets 18 and 19 are paired and the lamps of each pair are arranged in series so that when the operating circuit for either pair is closed, both lamps will light to indicate the direction in which the vehicle is turning. 20 For example, if the steering post 5 should be turned to the left to engage the contact 14 with the left hand segment 11, as viewed in Figure 1, a circuit is closed extending from the battery 20 through the switch 21, 25 which may be the ignition switch of the engine, contact 14, the engaged segment 11 and its associated terminal post, conductor 22, the left hand lamps of the sets 18 and 19 in series and from thence to the other terminal of the battery 20.

From the foregoing description, it will be obvious that the invention provides a direction indicating mechanism for vehicles, the

switching device of which may be readily applied in position on the steering post of 35 the vehicle and which will effectively operate to control the direction indicating signals in accordance with the movements of said steering post.

What is claimed is:

In a signaling mechanism, the combination with a rotatable member; of a switching device including a casing through which said rotatable member extends, arcuate contact segments mounted in opposite sides of 40 said casing in spaced relation with respect to each other and to the wall of the casing, arcuate insulating members interposed in the space between said segments and the wall of the casing and each having an arcuate recess in the inner face thereof adjacent the associated 45 arcuate segment, means extending through each insulating member and its associated segment at adjacent ends thereof for securing said segment in position, an arcuate adjusting plate interposed between each insulating member and associated segment and disposed in the recess of said insulating member, adjusting means for each adjusting 50 plate extending through said casing and insulating member and engageable with said plate, and a contact carried by said rotatable member and movable therewith into engagement with either one of said contact segments.

EDWARD JOSEPH WILSON, JR.
